UNITED STATES PATENT OFFICE.

ANTON KULICH, OF BROOKLYN, NEW YORK.

BUREAU-BED.

SPECIFICATION forming part of Letters Patent No. 349,723, dated September 28, 1886.

Application filed December 16, 1885. Serial No. 185,805. (No model.)

To all whom it may concern:

Be it known that I, ANTON KULICH, of Brooklyn, in the county of Kings and State of New York, have invented certain new and useful Improvements in Bureau-Beds, of which the following is a specification.

This invention relates to improvements in the bureau-bed for which Letters Patent of the United States were granted to me heretofore, No. 328,895, dated October 20, 1885, the improvements being designed with a view to simplify the construction of the bed and reduce the size of the same; and the invention consists of a bureau-bed that embodies a casing composed of L-shaped side walls connected by transverse front and rear pieces, a hinged front panel having fixed side boards and top panels, of which one is hinged to the casing, the other to the front wall. The hinged 15 top panel is locked at right angles to the front panel when the latter is lowered into horizontal position. To the front panel is attached by locking devices a detachable spring-mattress, which is formed of a middle section, 20 a hinged head-section, and a hinged foot-section, which latter is provided with hinged legs and a hinged foot-board. The middle and foot sections of the spring-frame are connected by inclined straps attached to the 25 frames of said sections, the pivot-connection being made above the sections, so as to leave the required space for the mattress between them when they are folded up for being stored away in the casing.

30 In the accompanying drawings, Figure 1 represents a front elevation of my improved bureau-bed. Fig. 2 is a side elevation of the same. Fig. 3 is a vertical longitudinal section of the same, showing it arranged as a bed. Fig. 4 is a plan of Fig. 3, with part broken away. Fig. 5 is a vertical longitudinal section of the bed, showing it in folded-up state as a bureau; and Figs. 6 and 7 are details showing the connection of the top panel with 35 the hinged front panel of the casing.

Similar letters of reference indicate corresponding parts.

A in the drawings represents the casing of my improved bureau-bed, which is composed 40 of two L-shaped side walls, A' A', that are connected by transverse top and bottom pieces,

a a', at the rear part, and by a low front wall, b. To the front wall, b, is hinged a front panel, A², which is provided at both sides with fixed side boards, a², that fit into the open parts of the L-shaped side walls, and form with the same the side walls of the casing when the bed is folded up into a bureau, as shown in Fig. 1. The front wall, A², is provided with handles, ring-shaped pulls, or other devices, 55 in imitation of the handles of the bureau-drawers. To the upper edge of the front panel, A², is hinged a top panel, a³, that is equal in width to the side boards, a², so as to close the same, while the L-shaped side walls, A', are 60 closed by a rear top panel, a⁴, that is swung into upright position and supported by folding 65 braces a⁵, as shown in Figs. 3 and 5.

To the front panel, A², is attached, by means of pivoted retaining-hooks d d, a spring-mattress, B B', which can be readily detached from the panel A² on swinging the hooks d d side-wise of the bottom slats of the spring-mattress B.

The spring-mattress B B' is made of three 70 sections, a middle section, B, a hinged foot-section, B', which is adapted to fold on the middle section, and of a head-section, B², that is hinged by inclined straps e e' to the middle section in the manner fully described in the 75 patent hereinbefore referred to. The middle section only is held by the fastening devices on the front panel, A², the frame of the foot-section of the mattress being hinged to the panel of the middle section of the mattress, as shown 80 in Fig. 4. When the middle section is unlocked from the front panel, A², said middle section and the foot-section hinged to the same can easily be withdrawn and removed, as the 85 mattress is only held on the front panel by the locking device engaging the middle section.

The middle section, B, of the spring-mattress is somewhat larger than the front panel, A², of the casing A, and extended beyond its hinge-connection with the front wall, b, into 90 the casing A, as shown in Fig. 3. The foot-section B' is made of the same size as the middle section, B, which gives a greater length for the bed, while the head-section is reduced in width. The foot-section B' is provided with 95 a hinged foot-board, f, and hinged supporting-legs f' f', the foot-board and legs being folded 100

onto the foot-section when the same is folded up on the middle section, as shown in Fig. 5.

The middle and foot sections, B B', of the spring-mattress are connected by means of inclined straps g g' , united by pivots g^2 above the mattress, so as to leave sufficient space between the mattress-sections B B' for folding up a horse-hair mattress, C, with said section, as shown in Fig. 5. The hinged top panel, a^2 , is locked at right angles to the front panel, A^2 , when the same is lowered into horizontal position, by a pivoted latch, h , which engages a keeper, h' , at the upper edge of the front panel, A^2 , as shown in Figs. 6 and 7, so as to form a rigid support for the front panel and spring-mattress, which does not change its position even when the bureau-bed is moved on the floor. When folding up the bed, the keeper h' fits into a recess, h^2 , of the top panel, a^2 . (Shown in Figs. 6 and 7.)

The bureau-bed is changed from a bureau into a bed, and vice versa, in the same manner as the bureau-bed described in my prior patent.

My improved construction has the advantage that the spring-mattress forms a separate part that can be readily detached for repairing or cleaning the same. Another advantage is that the mattress-sections take up a smaller space when folded up and bring the head-section lower down, so that the size of the casing can be materially reduced, owing to the more advantageous disposition of the sections in the space within the same as compared to my prior patent. The L-shaped side walls of the casing have the advantage that the head is left free for the better access of the air, while the hinged rear top panel increases the height of the casing and forms a head board when swung into upright position.

Having thus described my invention, I claim as new and desire to secure by Letters Patent—

1. The combination of a supporting-easing having hinged front and top panels with a detachable spring-mattress made of folding sec-

tions, and devices for attaching the spring-mattress to the front panel of the casing, substantially as set forth. 45

2. The combination of a casing having upright side walls and transverse front and rear walls, a front panel hinged to the front wall, a top panel hinged to the front panel, devices for locking the top panel at right angles to the front panel, a detachable spring-mattress formed of folding sections and a hinged head-section, and devices for attaching the folding spring-mattress to the front panel, substantially as set forth. 50

3. The combination of a casing having upright side walls and a transverse front wall, a front panel hinged to said front wall, a top panel hinged to the front panel, devices for locking the top panel at right angles to the front panel, a detachable spring-mattress formed of a middle section, a hinged foot-section and a hinged head-section, and devices for attaching the middle section to the front panel, the middle and foot sections being of larger size than the front panel, so as to extend when folded into the lower part of the casing, substantially as set forth. 60

4. The combination of a supporting-easing having hinged front panel, a top panel hinged to the front panel, devices for locking the top panel at right angles to the front panel, a detachable spring-mattress formed of a middle section attached to the front panel, a hinged head-section and a hinged foot-section, the latter being pivoted to side straps of the middle section and provided with hinged supporting-legs at the outer end, substantially as set forth. 70

In testimony that I claim the foregoing as my invention I have signed my name in presence of two subscribing witnesses.

ANTON KULICH.
